DESIGN FOR A CAMERA

Walter D. Teague, New York, N. Y., assignor to
Eastman Kodak Company, Rochester, N. Y., a
corporation of New Jersey

Application February 20, 1937, Serial No. 67,778

Term of patent 3½ years

To all whom it may concern:

Be it known that I, Walter D. Teague, a citizen of the United States of America, residing at New York city, in the county of New York and State of New York, have invented a new, original, and ornamental Design for Cameras, of which the following is a specification, reference being had to the accompanying drawing, forming a part thereof, in which—

Fig. 1 is a front elevation of a camera constructed in accordance with my new design, the camera being in an open or picture-taking position.

Fig. 2 is a rear elevation of the camera shown in Fig. 1.

Fig. 3 is a side elevation of the camera in a folded position.

Fig. 4 is a view similar to Fig. 3, but with the camera in an open or picture-taking position.

I claim:

The ornamental design for a camera as shown and described.

WALTER D. TEAGUE.
